DRAFTING MACHINE COUNTERBALANCE

John W. Harriman, Glendale, Mo.

Application June 19, 1941, Serial No. 398,706

16 Claims. (Cl. 33—79)

This invention relates to a drafting machine counterbalance.

It is known that the better types of drawing tables have a drawing board pivotally supported on an understructure permitting the angle of inclination of the board to be varied substantially through the 90° range from horizontal to vertical. When a drafting machine is used on such a board, the counterbalancing of the drafting machine when the board is tilted rapidly to angles of inclination between horizontal and vertical becomes a problem. For instance, when the head of the drafting machine is at rest at some point on the surface of the board inclined at 10° from horizontal and the board is then tilted to 45°, the head of the machine will slip to the bottom of the board. This tendency of the head of the machine to slide down the board can be corrected easily for any certain angle. The problem is to provide a counterbalancing force exerted on the head of the drafting machine that will automatically increase to the required amount or extent when the board is tilted to a steep angle, and also decrease instantly when the board is moved to a low angle approaching a horizontal position. With such a correctly variable force acting to counterbalance the weight of the drafting machine, it is possible to set the head in the center of the board when the board is at a low angle such, for instance, as 5°, and then rapidly increase this angle of inclination, even to 75° or more, without the head of the drafting machine moving from its position in the center of the board in spite of the much greater downward pull of the weight of the machine in the 75° position. At the same time, it must be possible to move the head freely over the surface of the board irrespective of the angle of inclination.

An object of the present invention is to provide a drafting machine counterbalance that will cooperate with the drafting machine in the manner stated and enable the machine to be moved rapidly from horizontal position, or a low degree of inclination from horizontal, without the head moving from its position on the board and at the same time leaving the head movable freely over the surface of the board irrespective of the angle of inclination to which the board is moved.

Another object of the invention is to provide a counterbalance device of the character indicated mounted for lateral movements along the upper edge of the board in accompaniment with the lateral movements of the drafting machine.

Other objects will appear from the following description, reference being made to the annexed drawings, in which—

Fig. 1 is a plan view of a drawing table and a drafting machine mounted thereon and equipped with the present invention.

Fig. 2 is an enlarged cross-sectional view of the drawing table on the line 2—2 of Fig. 1.

Fig. 3 is a sectional view, further enlarged, on the line 3—3 of Fig. 2.

5 Fig. 4 is an enlarged sectional view on the line 4—4 of Fig. 2.

Fig. 5 is a sectional view of the drawing table similar to Fig. 2, showing a modification of the invention.

10 Fig. 6 is a sectional view on the line 6—6 of Fig. 5.

Fig. 7 is a sectional view on the line 7—7 of Fig. 6.

Fig. 8 is a plan view of a drawing table and a 15 drafting machine mounted thereon and equipped with a laterally movable counterbalance mechanism connected with the drafting machine.

Fig. 9 is an enlarged sectional view on the line 9—9 of Fig. 8.

20 Fig. 10 is a sectional view of the drawing table similar to Fig. 9, showing the counterbalance rail wholly supported by the carriage of the counterbalance device.

The drawing board 1 is supported on the understructure 2 by a horizontal pivot 3. It is known that the board 1 is movable about the horizontal pivot 3 to different adjustments from a horizontal position to a vertical position. The drafting machine is mounted on the table and 25 comprises a head 4 freely movable over the surface of the board to any desired position thereon. It is in connection with this conventional type of drawing table that the present invention is shown, although it may be used in connection 30 with other types of drawing tables having the drawing board movable from horizontal to different inclined positions.

Essential features of the invention are a counterweight 5 supported for movements along an 35 inclined rail 6 projecting downwardly and forwardly from the rear and below the drawing board 1, and a cord 7 releasably connected with the counterweight at 10 and passing over a pulley 8 to the drafting machine to which it is attached.

45 The rail 6 extends transversely of the plane of the axis of the horizontal pivot 3. By cooperation of the counterweight with the drafting machine which is located on the drawing board, the drawing board may be moved to any angle of inclination 50 from horizontal position and the drafting machine will be held from accidental displacement along the drawing board and, at the same time, will remain freely movable over the surface of the board irrespective of the angle of inclination thereof.

The pulley 8 is mounted on a bracket 9 attached to the upper or rear side edge of the drawing board. The cord 7 has one end secured to the bracket 9 by an attachment 10' and is engaged with a pulley 11 on the counterweight 5

and passes between a pair of small guide pulleys 12 mounted on the bracket 9 adjacent to the pulley 8 and between said pulley 8 and the drafting machine. This permits the drafting machine to be moved to various positions over the drawing board, as indicated in Fig. 1, without disengaging the cord 7.

The counterweight rail 6 has one end connected with the bracket 9 by a pivot device 13. In the arrangement shown in Fig. 2, the opposite end of the rail 6 extends for sliding movements through a supporting guide 14 having a pivot 15 mounted in a bracket 16 attached to a cross member 17 of the drawing table. Rollers 18 rotatively support the counterweight 5 to facilitate its movement along the rail 6 and minimize friction.

In Fig. 5, the lower end of the rail 6 extends through a slot 19 formed in a bracket 20 attached directly to the underside of the drawing board 1. The rail 6 may be secured at any angle of inclination with respect to the drawing board and maintained in constant relationship thereto by a clamping device comprising a shoulder 21 on the rail 6 abutting against the bracket 20 and a nut 22 screwed on the lower end of the rail 6 at the opposite side of the bracket 20. When the nut 22 is tightened, the rail 6 will be held in fixed relationship with respect to the drawing board 1. By loosening the nut 22, the rail 6 may be moved to any other angle of inclination within the length of the slot 19 and secured in that position by tightening the nut 22. Also, the rollers 18 may be omitted from the counterweight 5, leaving the counterweight mounted directly on the rail 6 for sliding movements.

In Figs. 8 and 9, the counterbalance mechanism is mounted for lateral movements along the drawing board with the head 4 of the drafting machine. In this arrangement, the pulley 8' is rotatively supported in a bracket 9' which carries two laterally spaced rollers 23 operating against a rail 24 attached to the upper edge of the drawing board 1, and a pair of laterally spaced rollers 25 operating on a rail 26 attached to the upper margin of the drawing board 1. The counterweight rail 6' has its upper end attached to the bracket 9' and its lower end equipped with a roller 27 operating along a rail 28 supported by the understructure of the table parallel with the rails 24 and 26. The counterweight 5' is connected with the head 4 of the drafting machine by a cord 1' passing between rollers 12' on the bracket 9' and around a roller 11' mounted on the counterweight. The opposite end of the cord 1' from that which is attached to the head 4 of the drafting machine is attached to the bracket 9' by a fastener 29. Obviously, the counterweight 5' may be of the type shown in Fig. 2 and be provided with rollers to operate along the counterweight rail 6', or may slide along said rail, as desired.

In the variation shown in Fig. 10, a bracket 30 supports a pair of rollers 31 operating against a rail 32 attached to the upper edge of the drawing board 1, and also supports a pair of laterally spaced rollers 33 operating on a rail 34 attached to the underside of the drawing board. The rails 32 and 34 are parallel with each other as, of course, are the rails 24 and 26. In this form of the invention, the counterweight rail 35 has its upper end rigidly attached to the bracket 30 and its lower end free from any supporting element and provided with an abutment 36 for the counterweight 37 mounted on said rail. In this

form of the device, the cord 7' has one end attached to the head 4 of the drafting machine and its opposite end attached to the bracket 30 by a fastener 38. This cord passes between guide rollers 39 on said bracket around the pulley 8' and around a roller 40 rotatively supported by the counterweight 37. In this form of the invention, the counterweight mechanism may move laterally along with the drafting machine the same as in the construction shown in Fig. 9. Obviously, the rail 35 can be attached to a bracket such as the bracket 9 constructed for rigid attachment to the drawing board.

From the foregoing, it is apparent that in either embodiment of the invention, the tendency of the drafting machine to slide downwardly along the drawing board when the latter is tilted from horizontal to any inclined position is resisted by the counterweight. The counterweight constitutes a variable force acting to counterbalance the weight of the drafting machine so that the drawing board may be tilted rapidly to any inclined position without displacing the drafting machine and, at the same time, leaving the drafting machine freely movable over the surface of the board. In the arrangement shown in Figs. 1 to 5, the counterbalance mechanism is in a fixed position whereas, in Figs. 8, 9 and 10, the counterbalance mechanism accompanies the drafting machine in its lateral movements along the drawing board.

The invention may be varied in other respects than in those specifically shown and described, and I contemplate such variations in the form and structure of the parts and their relative arrangement as may be needed. Such variations may be made without departure from the nature and principle of the invention.

I claim:

1. In a drawing board supported for swinging movements from a horizontal position to various angles of inclination from said position, and having a drafting machine attached to the drawing board and provided with a head movably mounted on said drawing board; a bracket supported by the upper portion of the drawing board, a counterweight guide rail having its upper end pivoted to said bracket, a guide for the lower end of said guide rail for supporting the same in different angular positions with respect to the drawing board according to the angular positions of the latter, a counterweight for the head of said drafting machine mounted on said guide rail, a cord attached to said bracket and to said head of the drafting machine, means for engaging an intermediate portion of said cord with said counterweight for counterbalancing said head of the drafting machine, and guide rollers on said bracket engaging and guiding said cord during movements thereof by said head of the drafting machine.

2. In a drawing board supported for pivotal swinging movements from a horizontal position to any desired angle of inclination from said horizontal position, and having a drafting machine attached to and provided with a head mounted for free movements over said drawing board; a bracket attached to the upper portion of the drawing board, a counterweight guide rail having one end pivoted to said bracket and diverging downwardly from the underside of the drawing board, a counterweight mounted for movements along said rail, a pulley supported by said counterweight, guide pulleys supported by said bracket, and a cord engaging all of said

pulleys and having one end attached to said bracket and the opposite end detachably secured to said head of the drafting machine and holding said head from accidental displacement along the drawing board when said board is moved to angular positions from the horizontal.

3. In a drawing board supported for pivotal swinging movements from a horizontal position to any desired angle of inclination from said horizontal position, and having a drafting machine attached to and provided with a head mounted for free movements over said drawing board; a bracket attached to the upper portion of the drawing board, a counterweight guide rail pivoted to said bracket and diverging downwardly from the underside of the drawing board, a support for the lower end of said rail, a counterweight for said head of the drafting machine mounted for movements along said guide rail, a pulley supported by said counterweight, guide pulleys mounted on said bracket, and a cord attached to said bracket and extending downwardly therefrom around said pulley on said counterweight and also extending upwardly therefrom and engaging said pulleys on said bracket and having one end detachably secured to said head of the drafting machine.

4. In a drawing board supported for pivotal swinging movements from a horizontal position to any desired angle of inclination from said horizontal position, and having a drafting machine attached to and provided with a head mounted for free movements over said drawing board; a bracket attached to the upper edge of said drawing board, guide pulleys mounted on said bracket, a counterweight guide rail having one end pivoted to said bracket, a pivoted guide for the opposite end of said guide rail below the drawing board, a counterweight mounted for movements along said guide rail between said bracket and said guide, a pulley supported by said counterweight, and a cord attached to said bracket and looped around said last named pulley and engaging said pulleys on said bracket and having one end detachably secured to said head of the drafting machine.

5. In a drawing board supported for pivotal swinging movements from a horizontal position to any desired angle of inclination from said horizontal position, and having a drafting machine attached to and provided with a head mounted for free movements over said drawing board; a bracket attached to one edge of said drawing board, pulleys mounted on said bracket, a counterweight guide rail having one end pivoted to said bracket, a support for the opposite end of said guide rail below the drawing board, means cooperating with said support for holding said guide rail at different angles of inclination relative to said drawing board, a counterweight mounted for movements along said guide rail between said bracket and said support, a pulley mounted on said counterweight, a cord looped around said last named pulley and engaging said pulleys on said bracket, and means detachably securing said cord to said head of the drafting machine.

6. In a drawing board supported for pivotal swinging movements from a horizontal position to any desired angle of inclination from said horizontal position, and having a drafting machine attached to and provided with a head mounted for free movements over said drawing board; a bracket supported for lateral movements along one edge of said drawing board, a guide

rail having one end supported by said bracket, a support for the opposite end of said guide rail leaving said rail free to move laterally with said bracket, a counterweight mounted for movements along said rail between said bracket and said support, pulleys supported by said bracket and by said counterweight respectively, a cord attached to said bracket and looped around said pulley on said counterweight and engaging said pulleys on said bracket, and means detachably securing said cord to said head of the drafting machine.

7. In a drawing board supported for pivotal swinging movements from a horizontal position to any desired angle of inclination from said horizontal position, and having a drafting machine attached to and provided with a head mounted for free movements over said drawing board; a counterbalance mechanism supported for lateral movements along one edge of said drawing board, and means connecting said counterbalance mechanism with said head of the drafting machine to hold said head from accidental displacement when the drawing board is moved from horizontal position.

8. In a drawing board supported for pivotal swinging movements from a horizontal position to any desired angle of inclination from said horizontal position, and having a drafting machine attached to and provided with a head mounted for free movements over said drawing board; a counterbalance mechanism for said drafting machine, devices supporting said counterbalance mechanism for lateral movements along the drawing board in accompaniment with said drafting machine, and a cord connecting said counterbalance mechanism with said drafting machine for holding said machine from accidental displacement when the drawing board is moved from horizontal position.

9. In a drawing board supported for pivotal swinging movements from a horizontal position to any desired angle of inclination from said horizontal position, and having a drafting machine attached to and provided with a head mounted for free movements over said drawing board; a counterbalance mechanism for said head of the drafting machine, rails attached to said drawing board for supporting said counterbalance mechanism for lateral movements relative to said drawing board, and means detachably connecting said counterbalance mechanism with said head of the drafting machine.

10. In a drawing board supported for pivotal swinging movements from a horizontal position to any desired angle of inclination from said horizontal position, and having a drafting machine attached to and provided with a head mounted for free movements over said drawing board; a bracket, rails attached to said drawing board for supporting said bracket for lateral movements along said drawing board, a counterbalance device connected with said bracket for movement thereby during said lateral movements of said bracket, and a cord connecting said counterbalance device with said head of the drafting machine for holding the latter from accidental displacement when the drawing board is moved from horizontal position.

11. In a drawing board having an understructure and having a horizontal pivot supporting said board on said understructure for swinging movements about a horizontal axis from a horizontal position to various angles of inclination from said position, and also having a drafting

machine attached to said board and provided with a head movably mounted upon said board; a guide rail supported by and at the underside of the drawing board and extending forwardly from the rear portion of said board and transversely of the plane of said horizontal pivot, a counterweight for said drafting machine mounted for movements along said rail, a cord having one end rigidly connected with said drawing board and the opposite end attached to said head of said drafting machine and movably engaging and supporting said counterweight, and pulleys supported by the rear side of said drawing board engaging and supporting said cord between said head and said counterweight.

12. In a drafting machine having a drawing board provided with front and rear sides and having an understructure pivotally supporting said drawing board for swinging movements about a horizontal axis to various angles of inclination and thereby raising and lowering said front and rear sides, and also having a drafting machine attached to said board and provided with a head movably mounted upon said board; a guide rail extending transversely of the plane of said horizontal axis, means for supporting said guide rail spaced downwardly from the underside of the drawing board, a counterweight for said drafting machine supported for movements along said rail in accompaniment with the movements of said drafting machine relative to said board, a cord having one end rigidly attached with respect to said board and the opposite end attached to said head of said drafting machine and having an intermediate portion movably engaging and supporting said counterweight, and a pulley supported by the rear side of said drawing board for rotation about a horizontal axis and engaging and supporting said cord between said head and said counterweight.

13. In a drafting machine having a drawing board provided with front and rear sides and having an understructure pivotally supporting said drawing board for swinging movements about a horizontal axis to various angles of inclination and thereby raising and lowering said front and rear sides, and also having a drafting machine attached to said board and provided with a head movably mounted upon said board; a counterweight for said drafting machine, means for supporting and guiding said counterweight for movements forwardly and rearwardly below the drawing board transversely of said axis and complementary to any movements of said head above the drawing board, a cord having one end rigidly attached to the rear side of said drawing board and the opposite end attached to said head of the drafting machine, an anti-friction device connecting the intermediate portion of said cord with said counterweight for moving said counterweight when said head is moved above the drawing board as aforesaid, and a pulley supported by the rear portion of said drawing board for rotation about a horizontal axis and engaging said cord between said head and said anti-friction device for supporting and guiding said cord during movement thereof by said head.

14. In a drafting machine having a drawing board provided with front and rear sides and having an understructure pivotally supporting said drawing board for swinging movements about a horizontal axis to various angles of inclination and thereby raising and lowering said front and

5 rear sides, and also having a drafting machine attached to said board and provided with a head movably mounted upon said board; a guide rail below said drawing board and extending forwardly transversely of the plane of said horizontal axis and inclining downwardly and forwardly from said drawing board, means attached to said drawing board for supporting and moving said guide rail with said drawing board, a counterweight for said drafting machine supported by and for movements along said rail in accompaniment with the movements of said drafting machine relative to said board, a pulley supported by said counterweight, a cord engaging said pulley and having one end connected with said drawing board and the opposite end attached to said head, and a series of pulleys supported at the rear side of said drawing board supporting and preventing lateral displacement of said cord between said first pulley and said head.

15. In a drafting machine having a drawing board provided with front and rear sides and having an understructure pivotally supporting said drawing board for swinging movements about a horizontal axis to various angles of inclination and thereby raising and lowering said front and rear sides, and also having a drafting machine attached to said board and provided with a head movably mounted upon said board; a bracket supported by said drawing board at the rear side thereof, a counterweight guide rail having its rear end attached to and supported by said bracket, a guide for the forward end of said guide rail for supporting the same in a forwardly and downwardly extended position with respect to said drawing board, a counterweight for the head of said drafting machine mounted for movements along said guide rail, a cord having one end attached to said bracket and the opposite end attached to said head of the drafting machine, an anti-friction member supported by said counterweight for engaging an intermediate portion of said cord for counterbalancing said head of the drafting machine, and a series of guide rollers on said bracket engaging and guiding and preventing lateral displacement of said cord during movements thereof by said head of the drafting machine.

16. In a drafting machine having a drawing board provided with front and rear sides and having an understructure pivotally supporting said drawing board for swinging movements about a horizontal axis to various angles of inclination and thereby raising and lowering said front and rear sides, and also having a drafting machine attached to said board and provided with a head movably mounted upon said board; a bracket supported by said drawing board at the rear side thereof, a guide rail attached to said bracket and diverging downwardly and forwardly from and below the drawing board, a counterweight for said drafting machine supported for movements along said rail in accompaniment with the movements of said drafting machine relative to said board, a cord having one end rigidly attached to said bracket and the opposite end attached to said head of said drafting machine and having an intermediate portion connected with and supporting said counterweight, and pulleys supported by said bracket for engaging and preventing lateral displacement of said cord between said head and said counterweight.

JOHN W. HARRIMAN.
